CLAIM

The ornamental design for a motorcycle rim with spinning spoke, as shown and described.

DESCRIPTION

FIG. 1 is a perspective view of a motorcycle rim with spinning spoke in accordance with our new design; and, FIG. 2 is a side view thereof, the opposite side view being identical thereto.

The broken line showing the environment is for illustrative purposes only and forms no part of the claimed design.

1 Claim, 2 Drawing Sheets

FIG.1

FIG.2
